Patented Oct. 27, 1964

199,473

ELECTRIC PENCIL SHARPENER

Clyde F. Shuler, Philadelphia, Pa., assignor to Hunt Manufacturing Co., Camden, N.J., a corporation of Pennsylvania

Filed June 20, 1963, Ser. No. 75,441

Term of patent 14 years

(Cl. D74—21)

FIG. 1.

FIG. 2.

FIG. 3.

FIG. 4.

FIG. 5.

FIGURE 1 is a side elevation of an electric pencil sharpener showing my new design;

FIGURE 2 is a front elevation of the electric pencil sharpener of FIGURE 1;

FIGURE 3 is a rear elevation of the electric pencil sharpener of FIGURE 1;

FIGURE 4 is a top plan view of the electric pencil sharpener of FIGURE 1; and

FIGURE 5 is a bottom plan view of the electric pencil sharpener of FIGURE 1.

The electric cord is fragmentarily shown for convenience of illustration.

I claim:

The ornamental design for an electric pencil sharpener, as shown and described.
